GEORGE G. GOING, OF MIDDLETOWN, CONNECTICUT, ASSIGNOR TO REMINGTON TYPE-WRITER COMPANY, OF ILION, NEW YORK, A CORPORATION OF NEW YORK

TYPEWRITING MACHINE

Application filed February 21, 1928. Serial No. 255,971.

My invention relates to type actuating mechanism adapted particularly to typewriting machines and other machines employing printing type bars. The object of 5 the invention generally stated is to provide type-bar actuating-mechanism which is substantially noiseless in operation and is moreover readily adapted to small typewriting machines commonly called portable typewriters. A further object of the invention may be said to provide a modified construction of the type actuating mechanism which forms the subject-matter of my prior application Sr. No. 254,744, filed February 15, 1928.

To the above and other ends which will subsequently appear, my invention consists in the features of construction, combinations of devices, and arrangements of parts hereinafter described and particularly pointed out in the claims.

The preferred form of the invention is shown in the accompanying drawing, wherein

Fig. 1 is a front-to-rear fragmentary vertical sectional view taken about centrally of a typewriting machine embodying my invention, only so much of the machine being shown as is necessary to a full understanding of said invention.

Fig. 2 is a view showing a type action in operated position.

Fig. 3 is a vertical sectional view taken on a plane indicated by the section line 1—1 in Fig. 2 and looking in the direction of the arrows at said line.

Fig. 4 is a fragmentary view of a modification.

The type bars are pivoted in an arc of a 40 circle and arranged to strike on the front upper quarter of the platen. Each type bar 1 is adapted to turn about a fixed pivotal center, the full set of type bars being preferably pivoted on an arcuate pivot wire 2 which 45 is mounted on a type bar support or segment 3 of any suitable construction. The type bars may be disposed in guide slots 4, cut radially in the segment 3, the latter inclining upward and rearward towards the 50 platen 5 which is diagrammatically illus-

trated and is mounted on a suitable traveling carriage, not shown. Each type bar carries a type block 6 which is preferably provided with two types 7 and 8, the former being the lower case, and the latter the upper case type. Normally the lower case types 7 are effective to print, but the upper case types 8 may be rendered operative at will by relatively shifting the platen and the type bars in a known manner; as for example, by a shift of the platen as indicated by dotted lines in Fig. 1. As is well known, the type bars at and near the middle of the set or system are substantially straight throughout their lengths, while as the ends of the system are approached the type bars are bent near their type ends to varying extents in order to bring them in proper relationship with the printing points on the platen.

Key actuated means are provided for operating the type bars to swing them from normal position to a position in proximity to the printing point. The operating means for each type bar comprises a key lever 9 pivoted between its ends on a stationary pivot 10 and provided at its front end with a key cap or button 11, the rear arm of the key lever being provided with a curved contact face 12. This cooperates with the roof portion of a shoe-like part 13 of an angular lever 14 having a fixed pivot 15 and an upwardly extending rearwardly inclined arm 16. The shoe portion is shaped like an inverted U and loosely houses and covers the rear arm portion of the lever 9, the construction providing a yielding or lost motion connection between the key lever 9 and the sub-lever 14 and also preventing accidental derangement or disconnection of the two parts. The upper arm 16 of the sub-lever is pivotally connected at 17 with the rear end of a link 18, the front end whereof is pivotally connected at 19 with the upper arm of a second sub-lever 20. The set of sub-levers 20 are preferably arranged in guide slots 21 cut radially in an arcuate rib or lug 22 formed integrally with the segment 3 and projecting from the rear face thereof. An arcuate pivot wire 23 is seated

100

in a hole extending throughout the rib and bridges the guide slots 21 therein, said wire 23 providing a common pivot for the set of sub-levers 20. The longer arm of each of these sub-levers curves downward and forward and is pivotally connected at 24 with the rear end of a link 25 which extends forward and is pivotally connected at 26 with a member 27 which is also pivotally connected at 28 with a downward extension 1^a from the type bar. Preferably the member 27 is slotted to receive the end portions of the parts 25 and 1^a and the cross pins or rivets 26 and 28 are secured in the members 27 at opposite sides of the slotted portions thereof, said pins passing loosely through the parts 25 and 1^a. Normally, the set of type bars 1 extend forward and incline upward, their type ends being in contact with a rest or support 29 made of an arcuate strip of fibre or other suitable composition which is seated or housed in a stationary segmental support or rest 30. While each member 27 is additionally controlled as is to be explained, it may here be noted that said member performs a double function, being in effect a link or element of a toggle and also serving as a weight to effectuate the printing pressure of the type bar. At this point it need only be said that said member 27 is comprised in the actuating connection between a printing key lever 9 and its connected type bar 1 so that when the key 11 is adequately depressed the key lever 9 will turn on its fulcrum 10, actuating the sub-lever 14, transmitting a pull to the link 18 which will be effective to actuate the sub-lever 20, the lower arm of said lever operating to thrust or push the link 25 forward, transmitting an operating movement through the member 27 to the type bar 1 which will thereby be swung about its pivot 2 from a position of rest towards the platen. Preferably the key lever is arrested by an underlying stop 31 before the type bar reaches the platen, as will be understood from Fig. 2, which shows the key lever in contact with the stop 31, the type bar at the moment of such contact being in the dotted line position 1^x. The lost motion connection between the contact face 12 and the shoe 13 permits the type bar to continue its movement to printing position after the key lever has been arrested. After operation the parts of the type action are restored to normal position by means comprising a coiled spring 32 having its opposite ends hooked through holes and the upper arms of the associate sub-levers 14 and 20, the spring being disposed preferably just below the associate link 18.

In addition to the train of actuating devices above described, each type bar is associated with controlling means whereby it is slowed down as it approaches the platen and

is caused to coact with the platen with a minimum of noise and to be pressed against the platen with sufficient force to effect a proper imprint of the type. The controlling means for each type bar comprises a pair of connected toggles. One pair of said toggles is constituted by the links or members 33 and 34, the link 33 being preferably a two-part member comprising arms or parts 33^a arranged in parallelism and loosely embracing between them in normal position the sides of the associate type bar 1. The forward ends of the arms 33^a are fixedly connected by a cross pin or rivet 35 which passes loosely through a hole in the type bar near its type end and provides a pivotal connection between the type bar and the two-part link 33. The opposite ends of the arms 33^a curve downward and loosely embrace the sides of the rear end portion of the associate link 34 which is made in a single piece. The downwardly curving ends are fixedly connected by a cross pin or rivet 36 which passes loosely through a hole in the link 34 and provides a pivotal connection between the links 33 and 34. Normally as seen in Fig. 1, the two links are closely folded, the link 34 extending forward and upward under the link 33 and the type bar, and having a fixed pivot or anchorage 37 at its forward end. The said forward end is preferably received in a kerf or guide slot formed in a hanger 38, the pivot pin 37 bridging the slot in said hanger. The set of hangers 38 are adjustably supported in slots 39 cut radially in the upper side of a fixed segmental support 40 which is arranged in parallelism with the segment 3 and maintained in unvarying relationship therewith. The hangers 38 are adjustable fore and aft in the guide slots or seats 39 so as to afford adjustments or variable settings of the anchorages or pivots 37, and for this purpose the forward end portion of each hanger terminates in a downwardly extending lug or tit 41 which is received in a circular groove or cut-out 42 in the head 43 of a screw 44, the shank of which is threaded into a hole in the forward face of a segment 40. The construction is such that a close connection 41, 42 is established between the hanger 38 and the adjusting screw 43, 44 so that when the screw is threaded in or out the hanger is slid or adjusted in its slot-way to a corresponding extent. In order to hold the hanger 38 in adjusted position, clamping plates or washers 45 are arranged over the tops of the hangers, bridging the slots 39, said plates being secured in place by screws 46. If preferred a single arcuate plate secured by a sufficient number of screws may be employed for the whole set of hangers.

In addition to the toggle 33, 34 the controlling means comprises a second toggle, one link of which is constituted by the mem-

ber 27, the other link 47 being composed of two parallel arms or parts 47^a which loosely embrace the sides of the member 27 and also the rear portions of the links 33 and 34. The parts 47 are secured in fixed relationship near their opposite ends by cross pins or rivets 48 and 49. In the Figs. 1-3 construction, the pin 48 passes loosely through a hole in the lower end of the member 27 and provides a pivotal connection between the two parts or links 27 and 47, while the pin 49 likewise passes loosely through a hole in the link 34 and serves as a pivotal connection between said link 34 and the link 47. In order to prevent overthrow of the linkages a spring stop is preferably provided, constituted by a shouldered rivet 50 which is secured to the free ends of spring arms 51 preferably formed integrally with the parts or arms 47^a and so disposed that the stop 50 will coat with an edge or face of the member 27 when the parts are in operated position as shown in Fig. 2.

Upon depression of one of the keys the train of actuating devices will operate as has been described, causing the connected type bar to swing on its pivot 2 from the Fig. 1 position so that at the moment of arrest of the key lever 9 the type bar will be close to the platen in the dotted line position indicated at 1^x. During this operation of the type bar by its actuating devices, the controlling means comprising the two pairs of toggles 33, 34 and 27, 47 will be gradually opened or straightened as the result of their connection with the type bar and with the link 25. The energy acquired by the weighted member 27 and other parts in the train of controlling mechanism as well as the momentum of the type bar itself, in moving from the normal to the 1^x position, will be sufficient to complete the movement of the type bar to the printing position subsequent to the arrest of the key lever. The effect of the straightening of the toggle 33, 34 in moving to this position combined with the action of the other toggle 47, 27 will be to slow down the type bar and cause it to contact operatively with the platen with a minimum of noise. However, the momentum of the member 27 and connected parts will be effective to communicate sufficient pressure to the operating type to cause it to print fully and clearly. It will be seen that in the printing position the pivotal points 35, 36 and 37 will be nearly or substantially in line but that overthrow will be prevented by the members 47, 27 whose pivotal points 49, 48 and 28 will be prevented from aligning exactly by the coaction of the stop device 50 with the contiguous face of the part 27. After the printing operation, the parts will be restored to normal position assisted by their own re-

action, the effect of the restoring spring and the force of gravity.

It will be understood that the printing will be effected through the usual inking ribbon which will be controlled by any desired mechanism that may be found suitable for the purpose, although the ribbon and its mechanism are omitted from the drawing.

Changes may be effected without departing from the scope of my invention, and an example of such changes is shown in the modification illustrated in Fig. 4. In this modified construction the type bar itself and the train of key operated actuating devices, as well as the two sets of toggles which are comprised in the controlling means, are of substantially the same construction as in the Figs. 1-3 mechanism, although the adjacent end portions of the links 33 and 34 have a slightly different shape in order better to accommodate associate parts. However, the Fig. 4 construction differs from the Figs. 1-3 construction in that the link 47 instead of being connected to the link 34 as at 49, is re-set or adjusted about its pivot 48, being disconnected from the link 34 and pivotally connected instead at the point 52 to the link 33 just to the rear of its pivotal connection 36 with the link 34. The effect of this change is to give a more direct effect of the member 27 and associate parts on the toggle 33, 34.

It will be observed that by the present invention the drive link or actuating link 25 is connected to the weighted toggle member 27 and not directly to the type bar; that said link derives motion directly from an angular lever having a fixed fulcrum, preferably on the type bar segment itself, said lever in turn being linked to a second lever which is actuated by the key lever itself through a rolling contact, the construction affording a slow start and increasing speed until the type bar approaches close to the platen, from which point the double-toggle controlling-mechanism is effective to slow down the type bar and cause it to coat quietly with the platen but with an effective printing pressure; also that the weighted toggle member 27 is pivoted directly to the type bar, and its associate link 47 is connected to the main toggle, in one instance (Figs. 1-3) to the lower link thereof, and in the other instance (Fig. 4) to the upper link thereof; that the stop for preventing overthrow is spring-mounted on the second link of the weighted toggle; that the return spring is directly connected to both of the sub-levers; and that the main toggle is connected directly to the type bar and to a fixed pivot or anchorage which is adjustable so as to control the contactive engagement of the printing types with the platen.

Besides the changes heretofore described in connection with Fig. 4 other changes

may be made without departing from the spirit and scope of my invention.

What I claim as new and desire to secure Letters Patent, is:

- 5 1. The combination of a platen; a pivoted type bar; controlling-means therefor comprising two pairs of toggles, one member of one pair being pivoted to the type bar near the type head and the second member of the same pair having a stationary anchorage, one member of the second pair of toggles being pivoted directly to the said second member of the first pair, and the second member of the second pair being pivoted to 10 the type bar near its pivot; and key actuated means for operating the type bar comprising a drive link pivoted directly to the second member of the second pair of toggles.
- 15 2. The combination of a platen; a pivoted type bar; controlling-means therefor comprising two pairs of toggles, one member of one pair being pivoted to the type bar near the type head, and the second member of the same pair having stationary anchorage, one member of the second pair of toggles being pivoted directly to the said second member of the first pair, and the second member of the second pair being pivoted to the type bar near its pivot; and key actuated means for operating the type bar comprising a drive link pivoted directly 15 20 to the second member of the second pair of toggles, a sub-lever connected to said link, a second sub-lever, a link between said sub-levers, a key lever operative on said second sub-lever, and a coiled restoring-spring connected to both of said sub-levers.
- 25 3. The combination of a platen, a pivoted type bar; controlling means therefor comprising two pairs of toggles, one member of one pair being pivoted to the type bar near the type head and the second member of the same pair having stationary anchorage, one member of the second pair of toggles being pivoted directly to the said second member of the first pair, and the second member of the second pair being pivoted to the type bar near its pivot; and key actuated means for operating the type bar comprising a drive link pivoted directly to the second member of the second pair of toggles, a key lever, a stop to limit the downward stroke of the key lever, and lost motion connection between said key lever and said drive link.
- 30 4. The combination of a platen; a pivoted type bar; controlling means therefor comprising two pairs of toggles, one member of one pair being pivoted to the type bar near the type head and the second member of the same pair having stationary anchorage, one member of the second pair of toggles being pivoted directly to the said second member of the first pair, and the second member of the second pair being pivoted to the type bar near its pivot; and key actuated means for operating the type bar comprising a drive link pivoted directly to the second member of the second pair of toggles, a sub-lever connected to said link, a second sub-lever, a link between said sub-levers, and a key lever operative on said second sub-lever.
- 35 5. The combination of a platen; a pivoted type bar; controlling-means therefor comprising two pairs of toggles, one member of one pair being pivoted to the type bar near the type head, and the second member of the same pair having stationary anchorage, one member of the second pair of toggles being pivoted directly to the said second member of the first pair, and the second member of the second pair being pivoted to the type bar near its pivot; and key actuated means for operating the type bar comprising a drive link pivoted directly to the second member of the second pair of toggles, a sub-lever connected to said link, a second sub-lever, a link between said sub-levers, a key lever operative on said second sub-lever, and a lost motion connection between said key lever and said second sub-lever.
- 40 6. The combination of a platen; a pivoted type bar; controlling-means therefor comprising two pairs of toggles, one member of each pair being pivoted directly to the type bar; and key actuated means for operating the type bar comprising a drive link pivotally connected to a member of one of the toggles.
- 45 7. The combination of a platen; a pivoted type bar; controlling-means therefor comprising two pairs of toggles, one member of each pair being pivoted directly to the type bar; and key actuated means for operating the type bar comprising a drive link pivotally connected to a member of one of the toggles, a sub-lever having one arm connected to the drive link, a second link connected to the other arm of said sub-lever, a second sub-lever connected at one arm to said second link, and a key lever operative directly on the other arm of said second sub-lever.
- 50 8. The combination of a platen; a pivoted type bar; controlling-means therefor comprising two pairs of toggles, one member of each pair being pivoted directly to the type bar; and key actuated means for operating the type bar comprising a drive link pivotally connected to a member of one of the toggles, a sub-lever having one arm connected to the drive link, a second link connected to the other arm of said sub-lever, a second sub-lever connected to said second link, a key lever operative directly on said second sub-lever, and a draw spring directly connected with both of said sub-levers.
- 55 9. The combination of a platen; a pivoted type bar; key actuated means for operating and controlling the type bar to effect sub-

ing a drive link pivoted directly to the second member of the second pair of toggles, a sub-lever connected to said link; a second sub-lever, a link between said sub-levers, a key lever, a stop to limit the key lever stroke, 70 and a lost motion connection between said key lever and said second sub-lever.

5. The combination of a platen, a pivoted type bar, controlling-means for said type bar comprising two pairs of toggles, one member of one pair being pivoted to the type bar near the type head and the second member of the same pair having stationary anchorage, one member of the second pair of toggles being pivoted directly to the said second member of the first pair, and the second member of the second pair being pivoted to the type bar near its pivot; and key actuated means for operating the type bar comprising a drive link pivoted directly to the second member of the second pair of toggles, a sub-lever connected to said link, a second sub-lever, a link between said sub-levers, a key lever operative on said second sub-lever, and a coiled restoring-spring connected to both of said sub-levers.

6. The combination of a platen; a pivoted type bar; controlling-means therefor comprising two pairs of toggles, one member of each pair being pivoted directly to the type bar; and key actuated means for operating the type bar comprising a drive link pivotally connected to a member of one of the toggles.

7. The combination of a platen; a pivoted type bar; controlling-means therefor comprising two pairs of toggles, one member of each pair being pivoted directly to the type bar; and key actuated means for operating the type bar comprising a drive link pivotally connected to a member of one of the toggles, a sub-lever having one arm connected to the drive link, a second link connected to the other arm of said sub-lever, a second sub-lever connected at one arm to said second link, and a key lever operative directly on the other arm of said second sub-lever.

8. The combination of a platen; a pivoted type bar; controlling-means therefor comprising two pairs of toggles, one member of each pair being pivoted directly to the type bar; and key actuated means for operating the type bar comprising a drive link pivotally connected to a member of one of the toggles, a sub-lever having one arm connected to the drive link, a second link connected to the other arm of said sub-lever, a second sub-lever connected to said second link, a key lever operative directly on said second sub-lever, and a draw spring directly connected with both of said sub-levers.

9. The combination of a platen; a pivoted type bar; key actuated means for operating and controlling the type bar to effect sub-

- stantially a noiseless pressure imprint, said means comprising two pairs of toggles, one member of each pair being pivoted directly to the type bar, one of said pairs having a fixed anchorage, a finger key, and driving connections therefrom to one of said toggles for actuating the type bar from said key through said toggles; and devices for variably setting said anchorage.
10. The combination of a platen; a pivoted type bar; key actuated means for operating and controlling the type bar to effect substantially a noiseless pressure imprint, said means comprising two pairs of toggles, one member of each pair being pivoted directly to the type bar one near the type head thereof, the other member of the same pair that is connected near the type head having a stationary anchorage, a finger key, and driving connections therefrom to one of said toggles for actuating the type bar from said key through said toggles; and devices for affording variable settings of said anchorage.
15. 11. The combination of a platen; a pivoted type bar; key actuated means for operating and controlling the type bar to effect substantially a noiseless pressure imprint, said means comprising two pairs of toggles, one member of one pair being pivoted directly to the type bar near the type head and the second member of the same pair having a stationary anchorage which is adjustable to vary the effect of the toggle on the type bar, one member of the other pair of toggles being pivoted directly to the type bar near its pivot, a finger key, and driving connections therefrom to one of said toggles for actuating the type bar from the key through said toggles.
20. 12. The combination of a platen; a pivoted type bar; key actuated means for operating and controlling the type bar to effect substantially a noiseless pressure imprint, said means comprising two pairs of toggles, one member of one pair being pivoted directly to the type bar near the type head and the second member of the same pair having a stationary anchorage which is adjustable to vary the effect of the toggle on the type bar, one member of the other pair of toggles being pivoted directly to the type bar near its pivot, stop devices comprising a spring stop on one of the toggle members effective to prevent overthrow of both pairs of toggles, a finger key, and driving connections therefrom to one of said toggles for actuating the type bar from said key through said toggles.
25. 13. The combination of a platen; a pivoted type bar; key actuated means for operating and controlling the type bar to effect substantially a noiseless pressure imprint, said means comprising two pairs of toggles, one member of the first pair pivoted directly to the type bar and its companion member having a stationary anchorage, one element of the second pair of toggles being pivoted directly to said companion member, a spring stop mounted on said element of the second pair and cooperating with the second element of the said second pair to limit movement of both pairs of toggles, a key lever, an actuating device controlled thereby and with which said key lever has a loose connection that permits the toggles and type bar to move independently of the key lever after the latter has been arrested, and a link connected directly to said actuating device and a member of one of said toggles.
30. 14. The combination of a platen; a pivoted type bar; key actuated means for operating and controlling the type bar to effect substantially a noiseless pressure imprint, said means comprising two pairs of toggles, one member of one pair being pivoted directly to the type bar near the type head and the second member of the same pair having a stationary anchorage, one member of the second pair of toggles being pivoted directly to the said second member of the first pair and the second member of the second pair being pivoted directly to the type bar near its pivot, a key lever, an actuating device controlled thereby and with which said key lever has a loose connection that permits the toggles and type bar to move independently of the key lever after the latter has been arrested, and a link connected directly to said actuating device and a member of one of said toggles.
35. Signed at Middletown, in the county of Middlesex and State of Connecticut, this 17th day of February, A. D. 1928.
